PRESSURE-GENERATING DEVICE

Philip E. Kopp, Springfield, Ill.

Application September 14, 1949, Serial No. 115,677

8 Claims. (Cl. 103—37)

1

This invention relates to improvements in pressure-generating devices. More particularly this invention relates to improvements in devices that can generate hydraulic pressure.

It is therefore an object of the present invention to provide an improved device that can generate hydraulic pressure.

In the operation of machines that respond to hydraulic pressure to move and perform work, it is frequently desirable to supply a large volume of hydraulic fluid at low pressures to assure initial movement of the machines and then to supply a smaller volume of fluid at higher pressures to complete the movement of the machine and to exert the required final pressures. The combination of large volumes of fluid at low pressures and smaller volumes of fluid at higher pressures is very useful in the operation of hydraulically-actuated jacks, presses, rivet squeezers, and machine tools. Various methods and apparatus have been proposed to assure large volumes of fluid at low pressures and to assure smaller volumes of fluid at higher pressures; and one such apparatus consists of a pressure-generating device with a wobble plate that is mounted on a movable pivot. The wobble plate and its movable pivot will move automatically in response to changes in the output pressure, or they can be moved manually by the shifting of gears, to vary the length of stroke of the pistons of the pressure-generating device. Another such apparatus consists of a pressure-generating device with a motor shaft that carries a crank arm and that is axially reciprocable to adjust the position of the wobble plate. Reciprocation of the motor shaft and its crank arm changes the inclination of the wobble plate and thus varies the length of stroke of the pistons of the pressure-generating device. Still another such apparatus is a pressure-generating device that has a non-reciprocable motor shaft which carries a wobble plate, and that has a reciprocable cone which can be moved to adjust the angle of inclination of the wobble plate; the cone being reciprocable to adjust the angle of inclination of the wobble plate and thereby adjust the length of stroke of the pistons of the pressure-generating device. Other such apparatus consists of pressure-generating devices wherein the strokes of the pistons are fixed but wherein variable flow is attained by shifting a rotary valve or by rotating sloping-end pistons. In these various pressure-generating devices the variations in the output volume are effected by auxiliary mechanisms: the reciprocable motor shafts, the movable wobble plate pivots, the cones that adjust the

2

angles of inclination of the wobble plates, or the rotary valves and pistons that can be shifted by auxiliary, pressure-responsive plungers or by manually operated gear trains. Ordinarily these auxiliary pistons and gear trains will work; but they are not infallible and they offer considerable opportunity for errors in their construction and operation. Moreover, those pistons and gear trains are often complicated and are always expensive. For these reasons, such pressure-generating devices are objectionable. The present invention obviates these objections by providing a pressure-generating device with a wobble plate that responds directly to the forces exerted on the pressure-generating pistons of the device to move and change the output volume of the device. With such a device the pressure-generating pistons will deliver a large volume of hydraulic fluid at low pressures, but will, when the output pressure of the device increases, automatically, shift the position of the wobble plate of the device and thereby cause a reduction in the output volume of the device. It is therefore an object of the present invention to provide a pressure-generating device with pressure-generating pistons that can respond automatically to high output pressures of the device to shift the position of the wobble plate.

The present invention utilizes the shifting of the wobble plate to vary the output volume of the pressure-generating device by having that wobble plate act upon hollow pistons which have ports that can be uncovered during reciprocation of those pistons. Under low pressure conditions, the pistons will be in such a position that the ports of the pistons will be covered throughout the entire reciprocation of the pistons; and under high pressure conditions, the pistons will automatically assume a position wherein the ports will be uncovered during a part of the reciprocation of the pistons. The uncovering of the ports of the pistons will permit part of the fluid pumped by the pistons to pass through those ports, thus reducing the amount of fluid delivered to the outlet of the device. A number of springs will bias the pistons toward a position wherein the ports will be covered throughout the entire reciprocation of the pistons; but when the outlet pressure of the device is greater than the pressure exerted by the springs, the pistons will shift until the ports are uncovered during a part of the reciprocation of the pistons. As the outlet pressure continues to increase, the pistons will shift still further to uncover the ports for a greater part of their reciprocation. It is therefore an

object of the present invention to provide a pressure-generating device with hollow pistons that have ports which can be uncovered during part of the reciprocation of the pistons.

The pressure-generating device provided by the present invention has a cam that is splined to an intermediate shaft which is keyed to the shaft of the power source, usually an electric motor. This cam will normally respond to the action of the springs to move against the ends of the pistons; and as it rotates, this cam will successively force the pistons to telescope into the cylinders of the pressure-generating device. When the pressure at the discharge port of the device increases, the pistons will resist the forces exerted upon them by the cam and will cause the cam to move along the intermediate shaft. The splines permit such movement while maintaining rotation of the cam. It is therefore an object of the present invention to provide a splined cam that is supported by an intermediate shaft and is movable along that shaft in response to pressures exerted on the pressure-generating pistons of the device.

Each of the cylinders for the pressure-generating device of the present invention consists of two parts; the upper part being a hard metal sleeve and the lower part being a combination cylinder-extension and valve housing. Both parts are held in cylindrical openings in the body of the device; and each cylinder is provided with fluid-tight seals which prevent leakage of fluid past that cylinder. Additional seals are provided in the body of the pressure-generating device, adjacent the inlet and discharge valves, to prevent passage of fluid past those valves. Those seals are so constructed that they will positively prevent escape of fluid between surfaces which are carefully machined, but which are not ground and lapped. As a result, the body of the pressure-generating device provided by the present invention need not be ground and lapped. This greatly decreases the cost and time of manufacture since only the cylinders, pistons, valve elements and valve seats need be ground and lapped. With such a construction it is possible to generate and confine pressures as high as twenty thousand (20,000) pounds per square inch. It is therefore an object of the present invention to provide seals that prevent leakage of fluid past the hard metal sleeve cylinders and past the valve seats of a pressure-generating device; such seals being capable of coacting with machined surfaces to prevent leakage of fluid.

The body of the pressure-generating device provided by the present invention is made of one piece of metal, and it has bores therein to receive the cylinders, valve seats, and valve elements. By making the body of one piece of metal, the present invention avoids leakage due to stretched bolts and leaky gaskets, and it obviates the need of grinding mating faces of adjacent sections of bodies. Moreover, by being made of one piece of metal into which the cylinders, valve elements, and valve seats are fitted, the body of the pressure generating device can be made of lightweight metal. It is therefore an object of the present invention to provide a one-piece body for pressure-generating devices.

The pistons provided by the present invention will have a constant length of stroke, and the wobble plate will have a constant angle of inclination. In addition, the axis of the wobble plate, and the axis of the driving cam therefor, will intersect in the piston-engaging plane of the wobble plate. Such an arrangement makes it

possible to form right-circular cones on the ends of the pistons, and to make the angle of development of those cones equivalent to the angle of inclination of the wobble plate. Where this is done, line contact rather than point contact is assured between the wobble plate and each piston, virtually noiseless operation is assured, and virtually all wear is eliminated. It is therefore an object of the present invention to provide a wobble plate of fixed inclination, pistons of constant stroke, a piston-engaging plane on the wobble plate that includes the intersection of the axis of the wobble plate and the axis of the supporting shaft, and right-circular cones on the pistons that have an angle of development equivalent to the angle of inclination of the wobble plate.

Other and further objects and advantages of the present invention should become apparent from an examination of the drawing and accompanying description.

In the drawing and accompanying description several preferred embodiments of the present invention are shown and described but it is to be understood that the drawing and accompanying description are for the purpose of illustration only and do not limit the invention and that the invention will be defined by the appended claims.

In the drawing

Fig. 1 is a plan view of the one-piece body of a pressure-generating device that is made in accordance with the principles and teachings of the present invention.

Fig. 2 is a view of the bottom of the body which is shown in Fig. 1,

Fig. 3 is a cross-sectional, side view of the pressure-generating device of which the body of Figs. 1 and 2 is a part, and it is taken along the plane indicated by the line 3—3 in Fig. 1,

Fig. 4 is a cross-sectional side view of a portion of the device of Fig. 3, and it is taken along the plane indicated by the line 4—4 in Fig. 1,

Fig. 5 is a plan view of a recessed annular plate which is incorporated in the device of Fig. 3,

Fig. 6 is a cross-sectional side view of a modified form of pressure-generating device contemplated by the present invention.

Fig. 7 is a cross-sectional side view of another modified form of pressure-generating device contemplated by the present invention,

Fig. 8 is a cross-sectional view of another form of piston and cylinder usable with the pressure-generating devices contemplated by the present invention, and

Fig. 9 is a cross-sectional view of still another form of piston and cylinder.

Referring to the drawing in detail, the numeral 10 generally denotes the body of a pressure-generating device that is made in accordance with the principles and teachings of the present invention. The body 10 is cylindrical in form and it is made from one piece of metal. Ordinarily that body will be made of steel; but where reduced weight is desired, as in aircraft, the body 10 can be made of aluminum, magnesium, or alloys of those metals. The body 10 has a chamfer 12 at the periphery of the upper face thereof, and it has a shoulder 14 on that upper face which is spaced inwardly of the chamfer 12. A central recess 16 is formed in the upper face of the body 10; and a secondary recess 18, of smaller diameter and less depth, is provided at the base of the recess 16.

Spaced outwardly from the central recess 16 are four cylinder-receiving bores 20. These bores extend downwardly from the upper face of the

body 10 and they have lower portions 22 of larger diameter. The lower portions 22 extend upwardly from the lower face of the body, and they coact with the upper portions of bores 20 to provide abrupt shoulders in the body 10.

The lower end of the lower portion 22 of each of the bores 20 is provided with threads 24 opening to the lower face of the body 10. The four cylinder-receiving bores 20 are equally spaced from the central recess 16, and each bore 20 is 10 equally spaced from adjacent bores 20.

Also spaced outwardly from the central recess 16 are four valve-receiving bores 26. The radial distances between the valve-receiving bores 26 and the central recess 16 are greater than the radial distances between the cylinder-receiving bores 20 and the central recess 16. The valve-receiving bores 26 are equally spaced from each other; and their centers define straight lines which pass through the centers of the cylinder-receiving bores 20. Each of the valve-receiving bores 26 is spaced equally from adjacent cylinder-receiving bores 20. The valve-receiving bores 26 extend upwardly from the lower face of the body 10, but they do not extend completely through that body. Larger diameter, lower portions 28 of the bores 26 extend upwardly from the lower face of the body 10; the upper and lower portions of the bores 26 forming abrupt shoulders within the body 10. Threads 30 are provided at the lower ends of the lower portions 28 of the bores 26, and those threads open to the lower face of body 10.

The diameters of the cylinder-receiving bores 20 and the valve-receiving bores 26 are preferably identical, and the diameters of the lower portions 22 and 28 of bores 20 and 26 are also preferably identical. Where this is the case, the number of different tools that must be used in forming the bores in body 10 can be kept at a minimum. This not only reduces the number and kind of tools, but it also reduces the number of times the body 10 must be handled during its manufacture. All of this leads to reduced cost.

An annular groove 31 is formed in the body 10 adjacent each of the lower portions 22 of bores 20, and the grooves 31 open into those lower portions 22. An annular groove 33 is formed in the body 10 adjacent each of the lower portions 28 of bores 26, and the grooves 33 open into those lower portions 28. Ducts 32 extend between the annular grooves 31 and 33, and thus those ducts connect the bores 20 with the bores 26. The annular grooves 31 and 33 can be made by inserting a cutting tool into the body 10 through the bores 20 and 26. The ducts 32 are conveniently formed by drilling holes from the exterior of the body 10 to bores 26, and then drilling smaller holes from the bores 26 to the bores 20. The larger of the drilled openings will, in each instance, be closed by cylindrical plugs 34. Those plugs will be pressed into the larger of the drilled openings and then will be welded to the body 10. The plugs 34 will be made short enough so their inner ends terminate short of the bores 26. By this method, the ducts 32 can be made cheaply and simply while retaining the liquid-tight character of the body 10.

A discharge port 36 is provided at the center of the body 10, and that port opens to the bottom face of that body. Threads 38 are provided at the bottom of the discharge port 36, and those threads will receive a high pressure line, not shown, which will extend to the machine operated by the hydraulic fluid from the pressure-generating device. Four ducts 40 extend from

the bores 26 to the discharge port 36; and those ducts are conveniently formed by drilling two radial openings from the exterior of the body 10 through the bores 26. Each of the drilled holes 5 will pass through a bore 26, through the discharge port 36, and then terminate at a second bore 26. Once the ducts 40 have been formed, plugs 42 will be pressed into the outer ends of the drilled holes and welded to the body 10. The plugs 42 will be short enough to terminate short of the first bore 26. By this method, the ducts 40 can be made cheaply and simply while retaining the liquid-tight character of the body 10.

Four axially-directed holes 44 are provided in the body 10 for receipt of the shanks of machine screws 45. Those holes are contiguous with holes 46 of larger diameter; holes 46 receiving the heads of the screws 45. The screws 45 will preferably have slots across the tops thereof to receive the blade of a screw driver, and that screw driver can be inserted through the holes 46 to rotate the screws 45.

A chamfer 48 is provided at the periphery of the lower face of the body 10. That chamfer, together with chamfer 12, shoulder 14, recesses 16 and 18, the upper and lower portions of bores 20 and 26, threads 24, 30 and 38, annular grooves 31 and 33, ducts 32 and 40, discharge port 36, and holes 44 and 46 can all be made by usual and customary machining methods. None of these portions of the body 10 requires grinding or lapping; consequently the body 10 can be made quickly and cheaply by mass production methods.

The body 10 will receive the cylinders, pistons, valve elements, and valve seats of the pressure-generating device; and it will maintain all of those component parts in properly spaced, leak-proof relation. Each of those parts can be made individually and then assembled with the body 10. Thus, the pressure-generating device provided by the present invention lends itself well to manufacture on a sub-assembly basis.

A sleeve 50, preferably of hard steel, is inserted in the upper end of each of the cylinder-receiving bores 20. The sleeves 50 have flanges at the lower ends thereof, and those flanges will seat solidly against the shoulders between the upper and lower portions of the bores 20. The tolerances between the sleeves 50 and the bores 20 will be such that the sleeves can be pressed into position in those bores. The inner surfaces of the sleeves 50 will be ground and lapped to receive exteriorly ground and lapped pistons 52. These pistons will preferably be of hard steel, and they will have axially-directed bores 54 extending upwardly from the lower ends thereof. The axial bores 54 terminate a short distance below the upper ends of the pistons 52 by merging with transversely-extending bores 56. Each of the pistons 52 has four bores 56 extending through to the annular ports 57 at the surfaces of the pistons 52. By being ground and lapped, the pistons 52 and the sleeves 50 will have extremely close tolerances and will be capable of confining fluids under heavy pressures while permitting telescoping movement of the pistons relative to the sleeves.

A smaller diameter section is provided at the bottom of each of the pistons 52, and that section coacts with the rest of the piston to provide an abrupt shoulder 58. The shoulders 58 of the pistons 52 receive and hold washers 60; the washers 60 projecting slightly beyond the peripheries of the pistons 52.

A combined check-valve housing and cylinder-extension 62 of cylindrical form has an upper portion 61 provided with threads; that portion being spaced from the rest of housing 62 by an abrupt shoulder 70. The sleeves 50 and the upper ends of the housings 62 constitute the cylinders in which the pistons 52 reciprocate; those pistons being held closely by the sleeves 50. The threads on the upper portion of each housing 62 can be threaded into the threads 24 at the lower ends of the bores 20. The upper ends of the check-valve housings 62 are provided with axially-extending annular projections 64. Those projections will receive and hold O rings 66. The height of any one of the annular projections 64 is less than the thickness of any one of the O rings 66; and when the upper portions of the check-valve housings 62 are threaded into the threads 24 of lower portions 22, the O rings 66 will be compressed by their engagement with the flanged lower ends of the sleeves 50. Those O rings will coat with the flanged lower ends of sleeves 50, with the annular projections 64, and with the inner surfaces of the bores 20 to provide fluid-tight seals in the body 10. These seals will be primary seals, and they will keep hydraulic fluid from leaking upwardly between the exterior surfaces of sleeves 50 and the inner surfaces of bores 20. The engagement between the flanges on sleeves 50 and the shoulders between the upper and lower portions of bores 20 will provide secondary seals; and those seals add to the sealing effect of O rings 66.

The shoulders 70 on the check-valve housings 62 will limit the upward movement of the annular projections 64 on those housings. When fully seated against the lower face of the body 10, the shoulders 70 on the check-valve housings 62 will hold the annular projections 64 of those housings approximately four one thousandths (0.004) of an inch below the flanged lower ends of the sleeves 50. This arrangement assures heavy compression of the O rings 66 while assuring full seating of shoulders 70 against body 10. That full seating of shoulders 70 against the lower face of body 10 is used to provide primary seals which will keep hydraulic fluid from leaking down along the threads 24 of the body 10.

A transversely-extending duct 68 is provided in each of the housings 62, and those ducts extend completely through the walls of the housings 62. The ducts 68 are located so they register with the annular grooves 31 in the body 10. The transversely-extending ducts 68 are contiguous with the axial bores 72 in the check-valve housings 62.

An inwardly directed flange 74 is located adjacent the lower end of the axial bore 72 in each of the check-valve housings 62, and those flanges will receive the lower ends of the helical compression springs 76. The upper ends of the helical compression springs 76 will bear against the washers 60 on the pistons 52, and will bias those pistons upwardly. The lower ends of the pistons 52 extend within the upper ends of the helical springs 76, thus keeping the helical springs and pistons in assembled relation.

A ground and lapped seat 78 for a ground and lapped ball 82 is provided at the lower end of each of the check-valve housings 62; the seats 78 being held against shoulders 79 in the housings 62 by retaining rings 80. The retaining rings 80 are provided with hexagonal recesses to receive wrenches, and those rings will be threaded into the bottoms of the check-

valve housings 62. The engagement between the valve seats 78 and the shoulders 79 will be so tight that hydraulic fluid will be unable to leak past the exterior surfaces of the seats 78. 5 The balls 82 will be disposed above the seats 78, and they will normally be held in engagement with those seats by spiral compression springs 84 which have their upper ends bearing against the flanges 74. The engagement between the balls 82 and the seats 78 will be intimate enough to prevent leakage of hydraulic fluid when the balls are on the seats.

With this arrangement hydraulic fluid within the cylinders, formed by sleeves 50 and the upper ends of the check-valve housings 62, will positively be held against escape upwardly past the exteriors of sleeves 50 by O rings 66 and by the engagement between the flanges on those sleeves and the shoulders between the upper and lower portions of the bores 20. That fluid will also be held against escape upwardly by the close fit between pistons 52 and sleeves 50; and it will be held against escape downwardly by the engagement of shoulders 70 with body 10, the engagement of shoulders 79 with seats 78, and the engagement of balls 82 with seats 78. The only avenues open to fluid attempting to escape from the cylinders formed by sleeves 50 and housings 62 will be through ducts 68, grooves 31, and ducts 30 32.

A spiral spring 86 is located in each of the valve-receiving bores 26, and those springs normally press ground and lapped balls 88 downwardly against the ground and lapped valve seats 90 within the lower portions 28 of bores 26. The valve seats 90 are held against the shoulders between the upper and lower portions of bores 26 by the conjoint action of O rings 96 and retainers 92. Axially-directed annular projections 94 are formed on the upper ends of the retainers 92, and each of those projections is shorter than the thickness of any one of the O rings 96. The annular projections 94 are so dimensioned that when the shoulders 93 of the retainers 92 are seated against the lower face of the body 10, the upper end of each of the annular projections 94 will be spaced four one thousandths (0.004) of an inch below the adjacent valve seat 90. This makes possible heavy compression of the O rings 96 while permitting full seating of shoulders 93 against body 10. The heavy compression of O rings 96 enables those rings to positively prevent leakage of fluid downwardly past the lower face of valve seats 90, and also presses the seats 90 against the shoulders between the upper and lower portions of bores 26 with sufficient force to provide an initial seal. The full seating of the shoulders 93 against the lower face of body 10 will provide positive and primary seals against the leakage of fluid along threads 30.

Each of the retainers 92 has an axial bore 98, and that bore will register with the central opening of the adjacent valve seat 90. Extending radially outwardly from the bore 98 in each of the retainers 92 are four holes 100. These holes are in register with the annular grooves 33 in the body 10. Consequently, fluid passing from the bores 20 through the ducts 32 to the grooves 33 can pass into the bores 98 of the retainers 92 through the four radially-directed holes 100.

The O rings 96 will coat with the bores 26, seats 90 and projections 94 of retainers 92 to prevent leakage of fluid downward along the exterior of seats 90 while balls 88 will coat with 75 the seats 90 to prevent leakage of fluid between

balls and seats; and shoulders 93 will coact with body 10 to keep fluid from leaking downwardly past threads 30. Consequently, the fluid from ducts 32 can only flow uni-directionally upwardly past balls 88 and into ducts 40.

When the sleeves 50, the pistons 52, the O rings 66, the check-valve housings 62 with their springs, seats and balls, the springs 86, the balls 88, the valve seats 90, the O rings 96, and the retainers 92 are assembled with the cylindrical body 10 an integrated and unitary construction results. This construction will have fluid-tight integrity without any need of the gaskets customarily employed in the multi-section bodies of pressure-generating devices, and it eliminates the bolts customarily used to hold multi-section bodies in fluid-tight relation. In this way, the present invention avoids the troublesome leakage through gaskets and stretching of bolts experienced with multi-section bodies.

A cam housing 102 is constructed so it can engage the upper face of the cylindrical body 10. That cam housing has an annular face 104 that will surround and press against the shoulder 14 on body 10; and that face 104 will form a fluid-tight seal with the upper face of the body 10. The annular face 104 of the cam housing 102 will have four threaded openings 106 therethrough, and those openings will be in register with the openings 44 in body 10. The machine screws 45 will extend through the openings 46 and 44 and will then be seated in the threaded openings 106.

The upper end of the cam housing 102 has an end face 110 and a recess 112 in that end face. The end face 110 and the recess 112 receive the end face of an end bell 114 of an electric motor; the recess 112 receiving and centering a circular projection 116 on the end face of that end bell. The motor will have a rotatable shaft 117, and that shaft will have a key slot to receive a Woodruff key 115.

The cam housing 102 has a cylindrical bearing seat 108 adjacent the upper end thereof, and that bearing seat receives and holds the outer race of an anti-friction bearing 120. The inner race of the bearing 120 is pressed over a stud-carrying plate 122. The plate 122 carries six studs 124 which are all located on or to one side of the center line of the stud-carrying plate 122. The studs 124 are spaced thirty-six (36) degrees apart; the centers of the most remote studs lying on the center line of the plate 122. The lower ends of the studs 124 are chamfered, and those ends extend within helical compression springs 126. The studs 124 will guide and center the springs 126 and will hold those springs in assembled relation with the stud-carrying plate 122. The lower ends of the helical springs 126 will extend into recesses 130 in a recessed annular plate 128. There are six recesses 130 in the annular plate 128, and those recesses are in register with the six studs 124 carried by the stud-carrying plate 122. Holes 132, of lesser diameter than the recesses 130, are located in the bottoms of the recesses 130; and those holes permit fluid to drain out of the recesses 130.

The recesses 130 all are located on or to one side of the center line of the annular plate 128, and they are spaced apart thirty-six (36) degrees. Three balancing holes 134 are located in the other half of the annular plate 128; those balancing holes compensating for the removal of metal experienced in forming the recesses 130 and the holes 132. The weight of metal removed in forming the holes 134 should equal the differ-

ence between the total weight of the studs 124 and springs 126. The balancing holes 134 will be equi-spaced in the other half of the annular plate 128, as shown particularly in Figure 5, and the holes 134 will have their centers at the same distance from the axis of annular plate 128 as are recesses 130 and holes 132. With this arrangement the stud-carrying plate 122, the annular plate 128, studs 124, and the springs 126 will be statically and dynamically balanced.

The recessed annular plate 128 is pressed onto the upper end of a cam 136; and that cam has splines 138 at the interior surface thereof. Those splines will interfit with and be supported by splines 144 on an intermediate shaft 140 which has a bore 142 that telescopes over the motor shaft 117. The Woodruff key 115 will positively maintain the intermediate shaft 140 and the motor shaft 117 in assembled relation, and the splines 138 on the cam 136 will coact with the splines 144 on the intermediate shaft 140 to transmit rotation to cam 136 while permitting that cam to reciprocate along the intermediate shaft 140.

25 The lower end of the intermediate shaft 140 will be pressed into the inner race of an anti-friction bearing 146; and the bearing 146 will coact with the bearing 120 to guide and support the intermediate shaft 140. A spacing ring 148 will extend between the inner race of the bearing 146 and the lower end of the cam 136; that ring limiting downward movement of cam 136. That cam will be able to move upwardly along the intermediate shaft 140 while being driven by the splines 144 and 138.

30 The cam face of cam 136 is an annular surface inclined at an angle of eighty-one (81) degrees to the axis of the cam; and a generally-cylindrical portion 137 projects perpendicularly downward from that surface. The cam surface and the generally-cylindrical portion 137 receive and hold the upper race 150 of a combination wobble plate and anti-friction bearing. Balls 152 will bear against the upper race 150 and will also bear 35 against the lower race 154. The lower face of the lower race 154 will be ground flat, and it will bear against the upper ends of the pistons 52. The upper ends of the pistons 52 are ground and lapped to form right-circular cones which have an angle of development exactly equal to the angle of inclination of the wobble plate. That angle will be the same as the angle of inclination of the cam face: eighty-one (81) degrees. As a result, the lower face of the lower race 154 will be

40 precisely parallel to the upper ends of the pistons 52. In addition, the axis of the cam 136 and the axis of the generally-cylindrical portion 137 will intersect in the piston-engaging plane of the wobble plate. Such an arrangement makes it 45 possible to have line contact rather than point contact between the pistons and the wobble plate makes it possible to have virtually noiseless operation, and makes it possible to greatly minimize wear.

45 A return duct 156 is provided in one wall of the cam housing 102, and the upper end of that duct is provided with threads 158 to receive the return line from the machine operated by fluid from the pressure-generating device. A number 50 of ports 157 are located in the wall of the cam housing 102 above the level of cam 136. The cam housing will be set in a reservoir of hydraulic fluid, not shown, and the level of fluid in that reservoir must be above the bottoms of the check-

When power is applied to the motor, the motor shaft 117 will rotate; and that motor will, through the action of Woodruff key 115, rotate the intermediate shaft 140. The shaft 140 will rotate the stud-carrying plate 123, cam 136, recessed annular plate 128, and the upper race 150. The springs 126 will be stressed to bias the cam 136 against the spacing ring 148; and at low fluid pressures in the cylinders, the cam will rest against the ring 148. When the cam 136 is resting against the ring 148, rotation of that cam will cause the upper race 150 and balls 152 to force race 154 to produce a wobbling action. In the course of that wobbling action, the plate 154 will successively urge each of the pistons 52 downwardly against the action of springs 76. At any instant, two of the pistons 52 will be moving downwardly because of the action of lower race 154, and the other two pistons will be moving upwardly because of the action of springs 76. The lower race 154 of the wobble plate will not rotate but will wobble as the upper race 150 rotates with cam 136.

As the cam 136 continues to rotate, each of the plungers 52 will be moved upwardly and downwardly; the downward movement being due to the pressure exerted by the springs 126 upon the cam 136, and the upward movement being due to the springs 76 within the check-valve housings 62. The studs 124 and the springs 126 are located on that side of cam 136 which moves the pistons 52 downwardly; thus the upwardly and downwardly acting forces on the cam 136 are directly opposite each other. With this construction there will be no bending moments in the intermediate shaft 140, and no undue horizontally-acting forces on the bearings 120 and 146.

As the pistons 52 move upwardly, they will create a suction in the bores 72 which will raise the balls 82 off of the seats 78 and draw liquid into the bores 72. The liquid will flow into the bores 72 through the conjoint action of gravity and the suction caused by raising the pistons. When the pistons 52 start downwardly, under the force exerted by springs 126 and transmitted to the pistons by the wobble plate, the balls 82 will quickly seat on the valve seats 78 and prevent liquid flowing downwardly past those seats. Further downward movement of the pistons 52 will force liquid outwardly through the transverse ducts 68 in the valve housings 62, through the annular grooves 31, through the ducts 32, through grooves 33, through holes 100, through passages 98, and upwardly past the balls 88 and seats 90 into ducts 40. In passing the balls 88, the liquid will raise those balls off of the seats 90; and then when the pistons 52 start upwardly again the balls 88 will quickly seat against the valve seats 90. On the next upward strokes of the pistons 52, the balls 82 will be raised off of their seats and additional charges of liquid will enter the bores 72 of the housings 62; and the additional charges of liquid will be pumped through the transverse ducts 68, the grooves 31, the ducts 32, the grooves 33, the holes 100, the passages 98, and past the balls 88 and seats 90 into the ducts 40.

The motor will rotate at high speed; and the pressure-generating device will, through its four cylinders and pistons, provide an almost pulse-free flow of liquid to the discharge port 36. The amount of liquid delivered to the discharge port 36 will vary as the pressure of the liquid at that port varies; and that pressure will vary as the load on the machine operated by the liquid varies.

As the pressure on the fluid increases, the fluid in bores 72 will offer increased resistance to the pistons 52, and those pistons will cause compression of the springs 126. The compression of springs 126 will act to increase the force upon the pistons 52 and thus increase the force upon the fluid delivered to the discharge port 36. As the pressure on the fluid continues to increase, the springs 126 will continue to yield, and that yielding will permit the cam 136 to move upwardly along the intermediate shaft 140. Such upward movement of cam 136 will permit the pistons 52 to shift their paths of reciprocation upwardly relative to the cylinders 50. At low pressures those paths of reciprocation will permit the annular ports 57 to be wholly covered by the cylinders formed by sleeves 50 and housings 62. At higher pressures the paths of reciprocation of the pistons 52 will have been shifted upwardly so the ports 57 in the pistons 52 may be partially uncovered during the upper parts of their strokes. Where this occurs, a portion of the liquid within the axial bores 54 of the pistons 52 will be expelled from the pistons and into the cam housing 102 as the pistons 52 move downwardly. This bypassing action will stop as soon as the ports 57 are covered by the sleeves 50. As a result, the pistons 52 will, at high pressures, pump for only a portion of their strokes; the ratio of the lengths of the pumping and non-pumping portions of the strokes being determined by the pressure on the liquid and the resultant yielding of the springs 126. When the pressure on the liquid approaches its upper limit, the springs 126 will be compressed so fully that the ports 57 in the pistons will be covered only briefly during each stroke. Consequently, most of the fluid raised upwardly by the plungers 52 in their upward movement will be expelled into the cam housing 102, and very little fluid will be pumped downwardly for delivery to discharge port 36. However, that liquid which is delivered to discharge port 36 will be under very heavy pressure. With this construction, the pressure-generating device will provide a variable flow under variable pressure; exactly what is needed for jacks, presses, rivet squeezers, and machine tools.

One pressure-generating device made in accordance with the principles and teachings of the present invention had plungers reciprocable through a five sixteenths ($\frac{1}{16}$) inch stroke; and with a motor rotating at seventeen hundred and fifty (1750) revolutions per minute those pistons provided one hundred and ten (110) cubic inches of fluid per minute at one thousand (1000) pounds per square inch pressure. Upon an increase in the discharge pressure from one thousand (1000) to five thousand (5000) pounds per square inch, the flow decreased automatically to twenty two (22) cubic inches per minute. That flow was maintained indefinitely as long as the pressure remained at five thousand (5000) pounds per square inch; that flow increasing to one hundred and ten (110) cubic inches per minute when the pressure was relieved.

The fluid returning from the machine, operated by hydraulic pressure, will be discharged from duct 156 into the cam housing 102. That oil will directly lubricate the lower bearing 146 and will indirectly lubricate the upper bearing 120 by splashing about within the housing. The liquid will eventually rise to the level of the ports 157, and it will then spill out into the reservoir in which the cam housing 102 and the body 10 are positioned. One advantage of having the ports

151 above the level of the cam 136 is that the annular port 57 of the pistons 52 will always be surrounded by liquid and cannot become filled with air. The filling of those ducts with air would provide an air cushion within the pistons which would seriously affect the operation of the device. However, such air pockets cannot possibly form.

The ports 157 perform an additional function. The fluid returning from the machine operated thereby will be moving at a relatively high rate of speed and will tend to entrain air bubbles. That fluid will enter the chamber 102 and will begin to lose speed. Eventually, that fluid will find its way to the various ports 157 and will pass into the reservoir. The size and number of the ports 157 will be such that the fluid passing therethrough and into the reservoir will be moving at a much slower rate than it did when it passed through duct 156. In its travel at the lower speeds, the fluid can yield its entrained air bubbles.

Selection of the proper strength and size of springs 126, and selection of the proper diameters and strokes of pistons 52 will produce a pressure-generating device capable of delivering the desired volume of liquid at the desired pressure. Such devices can be used to provide prompt and automatic delivery of liquid at the various desired pressures.

If desired, as shown in Fig. 6, the variable flow feature of the pressure-generating device can be omitted. In such cases, a body 162 is substituted for the body 10. All parts of the body 162 will be identical to the parts of body 10 except for the elimination of shoulder 14 and the substitution of recess 163 for recesses 16 and 18. The exact same cylinders, O rings, check-valve housings, springs, valve seats, balls, and retainers will be used as are used with body 10.

The body 162 will fit into a recess 170 in a cam housing 166, and it will be suitably secured to that cam housing by bolts, not shown. The cam housing 166 will have overflow ports 168, and it will have a return duct 192; the outer end of duct 192 being provided with threads 194. The upper face of cam housing 166 has a recess 172 and that recess will receive and positively center the end bell 174 of a motor. The cam housing 166 has a bearing seat 176, and that bearing seat will receive and hold an anti-friction bearing 178. The outer race of that bearing will be pressed into the seat 176, and the inner race will be pressed over the upper end of the cam 180. The cam face will be inclined at an angle of eighty-one (81) degrees to the axis of the cam, and it will support a race 186. This race will coat with the balls 188 and the lower race 190 to provide a combination anti-friction bearing and wobble plate. The lower face of the lower race 190 will be ground and lapped and will bear against the upper ends of the pistons 164. Pistons 164 have the same general shape as pistons 52 but they are solid. Cam 180 is secured to motor shaft 184 by Woodruff key 182.

This construction possesses most of the desirable characteristics of the construction shown in Figs. 1-5. The only feature which is not possessed by this construction but which is possessed by the construction of Figs. 1-5 is the spring-supported cam plate and the hollow pistons. The construction shown in Fig. 6 is inexpensive, compact and simple.

Fig. 7 discloses a pressure-generating device which has a body 196 with four cylinder-receiving bores 198. Instead of opening to the upper

surface of the body, as do the cylinder-receiving bores 20 of body 10 in Figs. 1-4 and of body 162 in Fig. 6, the bores 198 open into coaxial bores 200 in the body 196. The bores 200 are connected together by ducts 202, and a central bore 204 extends between the ducts 202 and the upper face of the body 196. The bores 198 will receive sleeves 50, O rings 66, and check valve housings 62 with their springs, seats, and balls. The body 196 will have bores 26 with their balls, seats, O rings, springs, and retainers; and it will have ducts between bores 20 and 26 and between bores 26 and discharge port 36.

The bores 200 will confine and guide spring-encasing slides 206. These slides have axial bores that receive helical springs 208; the upper ends of those springs bearing against the upper ends of the bores within the slides 206. The lower ends of the springs 208 will bear against flanges 210; and the lower ends of the sleeves 210 will bear against the upper ends of pistons 212. The pistons 212 will be closely similar to the pistons 52 of Figs. 3 and 4 except that the upper ends of those pistons are flat. The slides 206 have projections 214 at the upper ends thereof, and those projections will engage the lower race 190 of a combination wobble plate and anti-friction bearing. This wobble plate and anti-friction bearing will be mounted on a cam 180 which in turn is keyed to the shaft 184 of a motor.

The springs 208 will bias the pistons 212 downwardly toward sleeves 50; and at low fluid pressures the pistons 212 will have paths of reciprocation wherein the annular ports 57 will be covered by the sleeves 52 throughout the entire paths of reciprocation of those pistons. At higher pressures, the springs 208 will be unable to hold the pistons 212 in those paths of reciprocation; instead, those springs will yield and permit those paths of reciprocation to shift upwardly. The amounts by which those paths of reciprocation shift will be determined directly by the fluid pressures acting on the pistons; the greater those pressures the greater the shifts will be. As those paths of reciprocation shift upwardly, some, then more, and finally almost all of the fluid pumped by the pistons 212 will pass into ducts 200 and then pass through duct 202 into the housing 167.

The pressure-generating device of Fig. 7 will provide variable pressures and variable volumes, and the volumes delivered by that device will automatically vary as the pressures vary. In this respect the device of Fig. 7 is similar to the device of Figs. 1-5. The particular advantage of the device of Figs. 1-5 over the device of Fig. 7 is that larger and heavier springs can be used. In addition, variations in the spring pressure of one of the individual springs would be compensated for by the other springs in the device of Figs. 1-5.

Fig. 8 discloses a sleeve 50 that encloses and guides a piston 216. This piston is solid rather than hollow; but it provides the effect of a hollow piston because it has an axially-directed port 218 in the surface thereof. The port 218 will serve the purpose of axial bore 54, transverse bore 56, and annular port 57 of piston 52. When the path of reciprocation of piston 216 is located so the port 218 is wholly enclosed by the sleeve 50, piston 216 will pump fluid downwardly throughout its entire down stroke. However, when the path of reciprocation of that piston shifts upwardly so the port 218 is uncovered during part of the stroke of that piston, some fluid can escape over the top

of sleeve 50 during the downward stroke of the piston.

Fig. 9 discloses a cylinder and piston that provide the effect of a hollow piston although the piston is solid throughout. A sleeve 220, generally similar to sleeve 50, has a port 222 in one portion of the inner periphery thereof. That port will normally be covered throughout the path of reciprocation of the piston 224; and where that is the case the piston 224 will pump fluid throughout its downward stroke. However, when the path of reciprocation of piston 224 is shifted upwardly, the undercut portion of piston 224 can permit fluid to enter port 222. Consequently, at such times some of the fluid will pass upwardly 15 through the port 222 as the piston 224 moves through its downward stroke. A washer 226 underlies the piston 224, and that washer is acted upon by a spring 228.

Whereas, several preferred embodiments of the present invention have been shown and described, it should be obvious to those skilled in the art that various changes may be made in the form of the invention without affecting the scope thereof.

What I claim is:

1. In a pressure-generating device, a cylinder, a piston reciprocable within said cylinder, a valve controlling flow of fluid into said cylinder, a second valve controlling flow of fluid out of said cylinder, a wobble plate that has a portion which forces said piston to move relative to said cylinder, a rotatable support for said wobble plate, said support being rotatable about one axis thereof, and a spring acting upon said rotatable support in a direction opposite to the action of said piston, said spring acting only on that part of the rotatable support which is coextensive with said portion of said wobble plate, whereby bending moments in said rotatable support are avoided.

2. In a pressure-generating device, a body, a bore within said body, and a seal for said body, said seal including an O ring disposable within said bore in said body, a surface against which the top of said O ring can bear, a surface that can bear against the bottom of said O ring, and an annular projection that is on one of said surfaces and is adjacent said O ring, said annular projection being shorter than the thickness of said O ring from top to bottom, said annular projection holding said O ring tightly within said bore and tightly against the other of said surfaces, the end of said annular projection being spaced from the other of said surfaces.

3. In a pressure-generating device that has a stationary cylinder, a hollow piston that is reciprocable within said cylinder and that has an elongated surface that bears against said cylinder, a port in said piston that opens to said elongated surface of said piston, a valved inlet at one end of said cylinder, a valved outlet intermediate the ends of said cylinder, said inlet and outlet constituting the only ports for said cylinder, a wobble plate that forces said piston to move relative to said cylinder, said cylinder and said piston being dimensioned so said piston can have a path of reciprocation wherein said port is intermediate said valved outlet and the end of said cylinder opposite said inlet and is completely covered by said stationary cylinder throughout 70 said path of reciprocation, said piston being capable of being shifted away from the said one end of said cylinder to a path of reciprocation wherein said port is covered by said stationary cylinder for only a part of said other path of re-

ciprocation, said piston forcing fluid toward said valved outlet during said part of said other path of reciprocation and permitting venting of fluid through said port during the rest of said other path of reciprocation.

4. In a pressure-generating device that has a stationary cylinder, a hollow piston that is reciprocable within said cylinder and that has an elongated surface that bears against said cylinder, a port in said piston that opens to said elongated surface of said piston, a valved inlet at one end of said cylinder, a valved outlet intermediate the ends of said cylinder, said inlet and outlet constituting the only ports for said cylinder, a wobble plate that forces said piston to move relative to said cylinder, said cylinder and said piston being dimensioned so said piston can have a path of reciprocation wherein said port is intermediate said valved outlet and the end of said cylinder opposite said inlet and is completely covered by said stationary cylinder throughout said path of reciprocation, said piston being capable of being shifted away from the said one end of said cylinder to a path of reciprocation wherein said port is covered by said stationary cylinder for only a part of said other path of reciprocation and permitting venting of fluid through said port during the rest of said other path of reciprocation, said piston being spring-biased toward the first said path of reciprocation but responding to increased fluid pressures at said valved outlet to shift to said other path of reciprocation.

5. In a pressure-generating device, a cylinder, a piston reciprocable within said cylinder, an inlet for fluid, an outlet for fluid, a spring that biases said piston away from one end of said cylinder, a wobble plate that has one portion to force said piston toward said one end of said cylinder and has another portion to permit said spring to move said piston away from said one end of said cylinder, a rotatable support for said wobble plate, said support being rotatable about one axis thereof and being reciprocable along said axis, and a second spring biasing said rotatable support and said wobble plate toward said piston and toward said one end of said cylinder, said second spring and said rotatable support and said wobble plate normally confining said piston to a predetermined path of reciprocation but responding to increased pressures on said piston to permit said piston to shift to a second path of reciprocation, said spring being in register with and acting upon the said one portion of said wobble plate.

6. In a pressure-generating device, a cylinder, a piston reciprocable within said cylinder, an inlet for fluid, an outlet for fluid, a spring that biases said piston away from one end of said cylinder, a wobble plate that has one portion to force said piston toward said one end of said cylinder and has another portion to permit said spring to move said piston away from said one end of said cylinder, a rotatable support for said wobble plate, said support being rotatable about one axis thereof and being reciprocable along said axis, and a second spring biasing said rotatable support and said wobble plate toward said piston and toward said one end of said cylinder, said second spring and said rotatable support and said wobble plate normally confining said piston to a predetermined path of reciprocation but responding to increased pressures on

said piston to permit said piston to shift to a second path of reciprocation, said spring being in register with and acting upon the said one portion of said wobble plate, said piston being hollow and having a port that opens to the exterior thereof intermediate the ends thereof, said port being covered by said cylinder throughout the said predetermined path of reciprocation but being exposed during part of said second path of reciprocation.

7. In a pressure-generating device, a cylinder, a piston reciprocable within said cylinder, an inlet for said cylinder that permits fluid to enter said cylinder, an outlet for said cylinder that permits fluid to leave said cylinder, a spring that biases said piston away from one end of said cylinder, a wobble plate that has one portion to force said piston toward said one end of said cylinder and has another portion to permit said spring to move said piston away from said one end of said cylinder, a rotatable support for said wobble plate, said support being rotatable about one axis thereof and being reciprocable along said axis, a plate that rotates about said axis but does not reciprocate along said axis, and a plurality of springs that extend between said rotatable support and said rotatable plate and bias said rotatable support for movement along said axis toward said one end of said cylinder, said plurality of spring being in register with the said one portion of said wobble plate, and interacting studs and recesses on said rotatable plate and rotatable support to confine and guide said plurality of springs, said plurality of springs and said rotatable support and said rotatable plate and said wobble plate normally confining said piston to a predetermined path of reciprocation but responding to increased pressures on said piston to permit said piston to shift to a second path of reciprocation.

8. In a pressure-generating device, a cylinder, a piston reciprocable within said cylinder, an in-

let for said cylinder that permits fluid to enter said cylinder, an outlet for said cylinder that permits fluid to leave said cylinder, a spring that biases said piston away from one end of said cylinder, a wobble plate that has one portion to force said piston toward said one end of said cylinder and has another portion to permit said spring to move said piston away from said one end of said cylinder, a rotatable support for said wobble plate, said support being rotatable about one axis thereof and being reciprocable along said axis, a plate that rotates about said axis but does not reciprocate along said axis, and a plurality of springs that extend between said rotatable support and said rotatable plate and bias said rotatable support for movement along said axis toward said one end of said cylinder, said plurality of springs being in register with the said one portion of said wobble plate, said plurality of springs and said rotatable support and said rotatable plate and said wobble plate normally confining said piston to a predetermined path of reciprocation but responding to increased pressures on said piston to permit said piston to shift to a second path of reciprocation.
